US00D608042S

(12) **United States Design Patent**
Wu et al.

(10) **Patent No.:** **US D608,042 S**
(45) **Date of Patent:** **** Jan. 12, 2010**

(54) **MULTI-DIRECTIONAL LIGHTING FIXTURE**

(75) Inventors: **Arthur Y. Wu**, Portland, OR (US);
James A. Doerr, Richmond, VA (US);
Michael D. Garten, Charlotte, NC (US);
David Rector, Spokane Valley, WA (US); **Virginia L. Broadbrooks**, Hendersonville, NC (US); **Dawn R. Kack**, Landrum, SC (US)

(73) Assignee: **Hubbell Incorporated**, Orange, CT (US)

(**) Term: **14 Years**

(21) Appl. No.: **29/311,782**

(22) Filed: **Jun. 18, 2009**

Related U.S. Application Data

(62) Division of application No. 29/309,129, filed on Jun. 25, 2008, now Pat. No. Des. 599,051.

(57) **CLAIM**

The ornamental design for a multi-directional lighting fixture, as shown and described.

DESCRIPTION

FIG. 1 is a right perspective view of the top of a multi-directional lighting fixture showing our new invention;

FIG. 2 is a left perspective view of the bottom of the fixture illustrated in FIG. 1;

FIG. 3 is a top plan view of the fixture illustrated in FIGS. 1 and 2;

FIG. 4 is a bottom plan view of the fixture illustrated in FIGS. 1-3;

FIG. 5 is a right side elevational view of the fixture illustrated in FIGS. 1-4, the left side elevational view being the mirror image thereof; and,

FIG. 6 is a left end elevational view of the fixture illustrated in FIGS. 1-5, the right end elevational view being the mirror image thereof.
